UNITED STATES PATENT OFFICE.

LOUIS COHN, OF NEW YORK, N. Y.

DESIGN FOR A CARD-CASE.

46,332.

Specification for Design.

Patented Sept. 1, 1914.

Application filed June 30, 1914. Serial No. 848,315. Term of patent 7 years.

To all whom it may concern:

Be it known that I, LOUIS COHN, a citizen of the United States, and a resident of New York city, borough of Bronx, in the State of New York, have invented a new, original, and ornamental Design for a Card-Case, of which the following is a specification, reference being had to the accompanying drawing forming part thereof.

The figure is a side view of a card case, showing my new design.

I claim:

The ornamental design for a card case, as shown.

LOUIS COHN.

Witnesses:

E. WOLF,
NORBERT SALTER.
